UNITED STATES PATENT OFFICE.

AUGUSTUS C. GRUHLKE, OF WATERLOO, INDIANA.

CIGAR-LIGHTER.

SPECIFICATION forming part of Letters Patent No. 623,982, dated July 18, 1899.

Application filed January 6, 1899. Serial No. 701,346. (No. model.)

To all whom it may concern:

Be it known that I, AUGUSTUS C. GRUHLKE, of Waterloo, in the county of De Kalb and State of Indiana, have invented an Improvement 5 in Cigar-Lighters, of which the following is a full and exact description.

My invention relates to an improvement in electric cigar-lighters adapted to be suspended from the ceiling or other support and to hang 10 in proximity to a show-case, for example, the lighter being especially adapted for use in stores or in other places where cigars are re-tailed.

The object of my invention is to provide 15 a lighter of the above-mentioned character which will be simple, durable, and economical and which may be automatically lighted by an electric spark when the lighter is drawn toward the person desiring the light, and 20 whereby when the lighter is released the flame will be instantly extinguished.

A further object of the invention is to so construct the lighter that the electric current cannot be short-circuited and that the lighter 25 may be operated in a strong current of air as successfully as when removed from drafts of air.

My present invention relates to the same general construction shown in Patent No. 30 613,140 and is an improvement on the same.

The invention consists in the novel construction and combination of the several parts, as will be hereinafter fully set forth, and pointed out in the claims.

Reference is made to the accompanying drawings, forming a part of this specification, in which similar characters of reference indicate corresponding parts in both figures.

Figure 1 is a vertical section through the 40 improved lighter. Fig. 2 is a horizontal section on the line 2 2 of Fig. 1.

A represents a tube of any desirable length, provided at its upper end with a tubular cap B, which is attached in any convenient manner. The tube A is connected at its lower 45 end with a second tube C, to which is attached a shield D, said shield comprising two opposing wings, suitably connected at one of their edges and being adapted to protect the flame 50 of the lighter from drafts or currents of air.

The upper tube A bears upon a metallic washer H, which fits snugly within the lower

tube C at a point near its upper end. Below the metallic washer H is the washer J, made of some insulating fiber, said washer J being 55 partially bored out, so as to receive the metallic washer I, and serving to insulate the washer I from the walls of the tube C and from the washer H. The washers I and J rest upon the cylindrical block R, made of some 60 insulating fiber, which bears at its lower end upon the shoulder a in the tube C and is prevented from rotating by the screw b.

Into the block R, at its upper end, is dovetailed the slotted metallic block L, in a position at right angles to the axis of the lighter and between the wings of the shield D, said block L passing through an opening c in the walls of the tube C, which opening is sufficiently large to prevent contact between the 70 walls of the tube C and the block L.

P is a metallic spring bent at right angles and soldered to the rear end of the block L and clamped and held in position by the washers I and J. In the slot d is pivoted the spark 75 point or tongue K, which is actuated in its movement by gravity and which normally hangs in a position at right angles to the block L. The tongue K is limited in its motion toward the lighter by the heel e hitting the under side of the spring P, as shown in dotted lines, the point f being thus prevented from coming in contact with the tube C and short-circuiting the electric current to be applied to the device, as will be hereinafter described. 85 It is also limited in its motion from the lighter when engaged with the burner-tube E, as described later, by the projection g striking the end of the spring P, and thus preventing the spring from being overstrained or broken. 90

The tube C is beveled at its lower end and a small chamber l is left below the block R.

An insulated conducting-wire m is attached to the metallic washer H, and a second insulated conducting-wire n is attached to the 95 metallic washer I, the two wires being carried up through the cap B to any generating device. The wires after passing through the cap B are preferably twisted together and may serve as a support for the lighter.

A receptacle G is provided to contain an illuminating fluid, and said receptacle is provided with a metallic nozzle E, which is pivotally connected with the lower front portion

of the shield D at F, and which in the normal position of the lighter will be in close contact at its upper end, which is beveled with the lower beveled edge of the tube C. The chamber l is thus seen to be immediately over the nozzle E. The nozzle E is provided with a suitable wick.

The path of the electric current is as follows: through the wire n to the washer I, thence to the spring P, to the block L, to the pivot o, to the tongue K, to its point f, through the wire m to the washer H, thence to the tube C, to the shield D, to the pivot F, to the nozzle E, to its tip p.

15 In the operation of the device the lighter is suspended from the ceiling or from any desired support within easy reach of a person desiring a light. The reservoir or receptacle G is filled with gasoline or other lighting fluid 20 capable of saturating the wick g. More or less vapor will at all times be present in the chamber l and will be held therein by the engagement of the nozzle E with the bottom of the chamber. The person desiring the 25 light will grasp the oil-receptacle G and draw it toward him. In so doing the upper edge or tip p of the nozzle E will be brought into contact with the spark-point f, which will gravitate toward said nozzle, a spark will be produced, and the vapor or gas set free from the chamber l will be ignited, and thus set fire to the volatile fluid saturating the wick. The 30 vapor or gas set free from the chamber l is prevented from dispersion through the air before the action of the spark by the wings D. After the light has been obtained the receptacle is released, the parts are returned by the 35 action of gravity to their normal positions, and the flame is extinguished by reason of 40 the nozzle being brought beneath the chamber l, thus cutting off the supply of air.

Having described my invention, what I desire to claim and to secure by Letters Patent is—

45 1. In an electric cigar-lighter, a current-conducting body, comprising an upper and lower member, the members having pivotal connection with each other, the combination with a block of insulating material, a metallic 50 block inserted in said insulating material, of a flat metallic spring provided at the upper edge of said metallic block, and an oscillating spark-point having pivotal connection with said metallic block, said oscillating point electrically charged and arranged to form a 55 contact with a member of said current-conducting body, substantially as and for the purpose described.

2. In an electric cigar-lighter, the current-conducting body comprising an upper and 60 lower member, the lower member having pivotal connection with said upper member, the combination with a block of insulating material, and a metallic block inserted in said in-

sulating material, of a flat metallic spring on 65 the upper edge of said metallic block, and a spark-point provided with heel and shoulder, said heel and shoulder arranged to be acted on by the metallic spring, whereby the spark-point is limited in its oscillation, said spark-point electrically charged and arranged to contact with the lower member, substantially as and in the manner described.

3. In a cigar-lighter, the combination of a body which is an electrical conductor, a block 75 of insulating fiber, a metallic block dovetailed in the insulating fiber, and a flat metallic spring provided at the upper edge of said metallic block, a spark-point pivotally connected to said metallic block, said spark-point 80 having an extension or heel which limits its motion toward the body of the lighter, and a small upward projection which limits its motion from the lighter, a reservoir provided with a nozzle which is an electrical conductor 85 and which is pivotally connected to said body, and wires conveying an electric current respectively to said spark-point and nozzle, substantially as and for the purpose described.

4. In a cigar-lighter, the combination of a 90 body which is an electrical conductor, a block of insulating fiber, a metallic block dovetailed in the insulating fiber and a flat metallic 95 spring provided at the upper edge of said metallic block, a spark-point pivotally connected to said metallic block, said spark-point having an extension or heel which limits its motion toward the body of the lighter, and a small upward projection which limits its motion from the lighter, a shield for the flame, 100 a gas-chamber, a reservoir provided with a nozzle which is an electrical conductor and which is pivotally connected to said body, and wires conducting an electric current respectively to said spark-point and to said nozzle, 105 substantially as and for the purpose described.

5. In an electric cigar-lighter, consisting of current-conducting body comprising an upper and lower member, the combination of a metallic block having insulated connection with the upper member, a flat spring arranged on the metallic block, a spark-point pivoted to said metallic block and in contact with said flat spring, the spark-point being provided with heel and shoulder whereby the oscillation of 115 the spark-point is controlled, an electrically-charged metallic washer contacting with said spring, with a reservoir attached to the lower member, said lower member having pivotal connection with the upper member of said 120 electrically-charged body, to permit its being swung outward and in contact with the spark-point, substantially as shown and for the purpose described.
